Primary Examiner — Khawaja Anwar

(57) **CLAIM**

The ornamental design for a refrigerated showcase coupled with transparent display as shown and described.

DESCRIPTION

1. Refrigerated showcase coupled with transparent display
1.1 : Perspective

1.2 : Front

1.3 : Back

1.4 : Left

1.5 : Right

1.6 : Top

1.7 : Bottom

1.8 : Perspective

1.9 : Exploded

The present design is a refrigerated showcases coupled with a transparent curved display; the present design ensures a high level of openness since a transparent display is applied to a refrigeration showcase, and helps to provide information or an advertisement on items in the showcase on a display; the broken lines indicate portions of the article that form no part of the claimed design; the fine lines in the drawings indicate a transparent display part; fig. 1.8 is a rear perspective view; fig. 1.9 is an exploded perspective view.

1 Claim, 9 Drawing Sheets
